TOY FOLDING STOCK BURP GUN

Mahlon Edward Hirsch, Fairview, Pa., assignor to Louis Marx & Co., Inc., a corporation of New York

Filed Feb. 8, 1966, Ser. No. 963

Term of patent 14 years

(Cl. D34—15)

FIG. 4

FIG. 7

FIG. 6

FIG. 5

FIG. 1 is a top plan view of a toy folding stock burp gun embodying my new design;

FIG. 2 is a side elevational view thereof;

FIG. 3 is a bottom plan view thereof;

FIG. 4 is a view similar to FIG. 2 showing the opposite side thereof;

FIG. 5 is a front end view thereof;

FIG. 6 is a rear end view thereof, and

FIG. 7 is a view similar to FIG. 2 showing the stock in a folded condition.

I claim:

The ornamental design for a toy folding stock burp gun, as shown.
